W. G. TARRANT,
BUILT UP WOODEN GIRDER.
APPLICATION FILED MAR. 27, 1919.

1,317,334.

Patented Sept. 30, 1919.

Inventor,
Walter George Tarrant
By his attorney,
Baldwin Wright

UNITED STATES PATENT OFFICE.

WALTER GEORGE TARRANT, OF BYFLEET, ENGLAND.

BUILT-UP WOODEN GIRDER.

1,317,334.

Specification of Letters Patent. Patented Sept. 30, 1919.

Application filed March 27, 1919. Serial No. 235,626.

To all whom it may concern:

Be it known that I, WALTER GEORGE TARRANT, a subject of the King of Great Britain, residing at Lake House, Byfleet, in the county of Surrey, England, have invented a new and useful Improved Built-Up Wooden Girder, of which the following is a specification.

This invention relates to the construction of light wooden girders, beams, spars, struts or other parts employed in the framing of aircraft, the main object being to attain maximum strength and rigidity in a necessarily extremely light structure.

My invention is illustrated by the accompanying drawings, in which Figure 1 is a side elevation showing two girder lengths constructed according to this invention and prepared for joining together in line, Fig. 2 is a side elevation showing the girder lengths joined together in line, Fig. 3 is a cross section on the line 3—3, Fig. 2, Fig. 4 is a cross section on the line 4—4, Fig. 2, Figs. 5 and 6 are detail views of a joining web of three ply veneer and Figs. 7 and 8 show details.

Figs. 1 and 2 show two lengths of girder each of which comprises four longitudinal members each comprising two wooden beams *a, a*, of tapered form as seen in cross section and having on their inner surfaces longitudinal grooves *b*. *c, c*, are inclined braces also formed of wood and having beads *d* formed on each side of each end: these beads lie in the grooves *b* as is clearly to be seen in Fig. 3, the braces being glued to the beads. The braces connecting two of the members are at right angles to the braces connecting the other members so that the whole structure is cruciform in cross section as seen in Fig. 4.

Reinforcing ribs *e* are applied at an angle to the grain and so shaped as to give great strength and resistance to deformation under the stresses imposed particularly at or near the middle of the length of the brace are glued to the braces. Beaded filling pieces *f* are inserted between the beams *a* of each member and are glued in position extending from one brace to the next.

The two girder lengths are connected together by a web *g* of ply wood of the same thickness as the braces *c*; this web has beads *d¹* which lie in the grooves *b* and is glued to the abutting ends of the members of the two lengths, the joints between the various mem-

bers being staggered so that they may not all lie in one transverse plane as shown in Figs. 1 and 2.

A convenient method of forming the beads 60 on opposite faces of otherwise smooth ply wood is illustrated in Fig. 6 and consists in boring through the wood a row of equally spaced holes and lacing through the holes from side to side in succession a string of 65 wood fiber *d¹*. When in position the string forms an interrupted bead on each side of the web and is hardened and fixed by the application of glue.

i, i, are slots in the web for allowing the 70 braces *c* to pass through it.

The two webs *g* connecting opposite members of the girder lengths are slotted as shown in Fig. 7 to enable them to be arranged at right angles to one another as 75 shown in Fig. 8.

What I claim is:—

1. The combination of two parallel members each comprising a pair of wooden beams each of which has on its inner face a longitudinal groove, and a plurality of inclined braces connecting the two members and having 80 at their ends beads lying in the grooves.

2. The combination of four members each comprising two wooden beams having longitudinal grooves on their inner faces and two series of inclined braces connecting opposite members and having at their ends beads lying in the grooves, the two series of braces being arranged in two planes which are at 90 right angles to one another.

3. The combination of two pairs of parallel members each comprising a pair of wooden beams each of which has on its inner face a longitudinal groove, one end of 95 each member of one pair butting against the end of a member of the other pair, a plurality of inclined braces connecting the two members of each pair and having at their ends beads lying in the grooves and the 100 braces connecting the two members of one pair lying in a plane at right angles to that in which lie the braces connecting the members of the other pair, and a beaded web connecting the pairs of members and having 105 its beads lying in the grooves.

4. The combination of two sets of four members each member comprising two wooden beams having longitudinal grooves on their inner faces, two series of inclined 110 braces connecting the opposite members of each set and having at their ends beads ly-

ing in the grooves, the two series of braces of each set being arranged at right angles to one another and one end of each member of one set butting against an end of a member of the other set, and two webs each of which is connected along each of two opposite edges to one member of each set, the two webs being arranged at right angles to one another.

10 5. The combination of two parallel members each comprising a pair of wooden

beams each of which has on its inner face a longitudinal groove, a plurality of inclined beaded braces connecting the two members and a plurality of beaded filling 15 pieces extending between the braces, the beads of the braces and filling pieces lying in the grooves.

In testimony that I claim the foregoing as my invention I have signed my name this 20 21st day of February, 1919.

WALTER GEORGE TARRANT.
